IMPULSE GENERATOR

Ben White Robins, Philadelphia, Pa., assignor to
 Radio Corporation of America, a corporation of
 Delaware

Application February 29, 1940, Serial No. 321,547

2 Claims. (Cl. 250—36)

This invention relates to impulse generators and more particularly to an apparatus for converting electric waves into short electric impulses which have the same frequency as the original wave or a frequency related thereto in the ratio of small whole numbers.

Impulse generators have been utilized in the art to provide short impulses for use with certain types of frequency meters, to provide marking impulses in connection with cathode ray oscilloscopes, or as harmonic generators. An example of the first-named use is found, for example, in a copending application of R. C. Sanders, Serial No. 248,577, filed December 30, 1938, Patent No. 2,228,367, January 14, 1941. This Sanders application describes a frequency indicator in which short voltage impulses of uniform amplitude are derived from an alternating wave and applied to an impulse counter. The principal object of this invention is to provide an improved circuit for obtaining sharp impulses from an alternating voltage which are of uniform duration, which are independent of variations in the amplitude and wave shape of the applied alternating voltage, and which are of the same frequency.

In accordance with a modification of this invention, a circuit is proposed by means of which the derived impulses may have a frequency less than the frequency of the applied alternating wave. Frequency dividers which accomplish the same result are known. Multivibrators and relaxation oscillators, for example, have commonly been used for this purpose. Such systems, however, are likely to have a free frequency at which they oscillate in the absence of a synchronizing voltage of sufficient amplitude to maintain the control. The proposed system differs in that the output voltage is a direct function of the frequency of the input voltage over a wide operating range. That is, the proposed circuit will not oscillate in the absence of a signal input. A further object of this invention is to provide an improved wave converter the output frequency of which bears a predetermined relation to the input frequency which may be expressible as ratios of small whole numbers.

This invention will be better understood from the following description considered in connection with the accompanying drawing. Its scope is indicated by the appended claims.

Referring to the drawing, Figure 1 is a circuit diagram of a wave converter; Figure 2 is a modification of the device illustrated in Figure 1; Figure 3 is a circuit diagram of a wave converter

modified to provide frequency division; and Figures 4 to 7 inclusive are curves illustrating the operation of this invention. Similar reference numerals refer to similar parts throughout the several figures of the drawing.

Referring to Fig. 1, a pair of terminals 9, 11 are connected between a source of alternating waves which is not shown, and an input transformer 13 having a center-tapped secondary winding 15. The center-tap of secondary 15 is connected to the cathode 17 of a thermionic triode 19, and to one terminal of a capacitor 21. One terminal of the secondary winding is connected to the grid 23 of thermionic tube 19 through a biasing battery 25, or its equivalent, and, optionally, through a grid current limiting resistor 27. The remaining secondary terminal is connected to the anode electrode 29 of a diode rectifier 31, the cathode 33 of which is connected to the remaining terminal of capacitor 21, and to an output terminal 35. A second output terminal 37 is connected to the anode 39 of thermionic tube 19. A load resistor 41 is connected between output terminals 35 and 37.

The operation of the device illustrated in Fig. 1 will be explained in connection with Figs. 4 and 5. The voltage which is applied to the input terminals 11 and 9 is an alternating wave having any desired wave shape. The voltage which is induced across half of the secondary of transformer 13 is applied to capacitor 21 through the rectifier 31. Consequently, charging current flows into the capacitor during each half of the applied alternating wave during which the anode 29 is positive with respect to its associated cathode 33. During the opposite half of the cycle, however, capacitor 21 retains its charge, so far as rectifier 31 is concerned, since the anode 29 is then negative with respect to its associated cathode 33. It is to be noted, therefore, that one charging impulse is applied to capacitor 21 for each cycle of the applied alternating wave. It is also to be noted that during the half cycle in which capacitor 21 receives a charge, the grid 23 of thermionic tube 19 is biased to a negative potential with respect to its cathode. Battery 25 also applies a negative potential to the grid, and it will therefore be appreciated that substantially no anode current flows during the first half cycle of the applied voltage. During the successive half cycle, however, a positive pulse is applied between the cathode and grid electrodes of the tube. The positive pulse is of sufficient amplitude to overcome the negative bias supplied by the biasing battery 25. The tube

then becomes conductive, and capacitor 21 discharges through the circuit including resistor 41 and the anode-cathode electron path of tube 19.

The output voltage is the voltage drop across anode resistor 41. Consequently, an impulse is applied to the output terminals 35, 37 each time capacitor 21 discharges through the resistor 41 and tube 19. The length of each impulse may be determined by suitably selecting the time constant of the capacitor 21 and the total resistance in the discharging circuit.

This cycle of operation is illustrated in Figs. 4 and 5, to which reference is now made. Curve E represents the applied voltage which is assumed to be substantially sinusoidal, although the invention is not limited to the application of such a wave. The dotted line Ec is the voltage across capacitor 21. This voltage increases from zero to maximum during each half cycle of the applied voltage in which the rectifier 31 is conductive. This half cycle is represented by that portion of curve E above the zero axis X-X. The voltage across the capacitor 21 remains substantially at its maximum value after the applied voltage has passed beyond its peak value. However, as the polarity of the applied wave reverses, the negative bias on the grid of tube 19 is reduced, the tube becomes conductive, and the capacitor is rapidly discharged. This process is repeated during each successive cycle of the applied voltage. Fig. 5 shows the relation of the output impulses to the input voltage E and the voltage Ec across capacitor 21. It is to be noted that the impulses correspond in time with the discharge of the capacitor.

Certain applications of this invention require the successive short impulses to have constant amplitudes. In the embodiment of this invention described above, this may be accomplished by regulating the amplitude of the applied alternating wave in any conventional manner. It will be appreciated, however, that variations in the amplitude of the applied wave will cause like variations in the amplitude of the output impulses.

Fig. 2 is the circuit diagram of a modification whereby the amplitudes of the successive impulses are maintained at a constant value in the presence of variations in the amplitude of the applied alternating wave. In such case, the voltage regulation referred to above will not be required.

Referring to Fig. 2, and considering that portion of the circuit between the input and terminals 35 and 37, input terminals 9 and 11 are connected to the primary of an input transformer 13, as before. Separate secondary windings 43 and 45 are provided. The first secondary winding 43 is connected to a thermionic tube 19 as described in connection with Fig. 1. The second secondary winding 45 is connected between the grid 47 and the cathode 49 of a second thermionic tube 51. Cathode 49 is also connected to the junction of resistor 41 and capacitor 21 and to terminal 35. The anode electrode 53 is connected to the positive terminal of a battery 55 the negative terminal of which is connected to the cathode 17 of the first thermionic tube 19.

During alternate half cycles of the applied alternating voltage, grid 47 becomes positive with respect to its associated cathode 49, and the anode-cathode impedance of the tube is reduced sufficiently to permit substantially the full voltage of the battery 55 to be impressed across capacitor 21. During intermediate half cycles of

the applied alternating voltage, a negative potential is applied to the grid 47, and capacitor 21 is unable to discharge through the charging circuit. However, as in the preceding illustration, first tube 19 becomes conductive during the intermediate half cycles and causes capacitor 21 to discharge through resistor 41 and tube 19. It will be appreciated that the voltage which is utilized to charge capacitor 21 is limited to a constant value somewhat less than the value of battery 55, so that the total charge, and consequently the amplitudes of the impulses developed across resistor 41 are independent of the amplitude of the applied alternating voltage.

As noted above, the embodiments of this invention illustrated in Fig. 1 and the portion of Fig. 2 so far described produce short voltage pulses which recur at the frequency of the applied alternating wave. The embodiment of this invention illustrated in the remaining portion of Fig. 2 provides a simplified system for selecting every second, third, fourth, or nth impulse, as desired. The terminals 35, 37 of the anode load resistor 41 are connected to a second capacitor 57 through a resistor 59 and a rectifier 61. A gas tube 63 and a resistor 65 are serially connected across the second capacitor 57. Output terminals 36 and 40 are connected across resistor 65.

Periodically repeated pulses of the type illustrated in Fig. 5 are produced across resistor 41 in the manner described above. Assuming that these impulses have such a polarity that the anode of rectifier 61 is made positive with respect to its associated cathode, a charging current will flow through resistor 59 into capacitor 57 during each of the successive pulses. The time constant of the charging circuit, however, is selected at such a value that the voltage across capacitor 57 does not reach the peak amplitude of the applied pulses during any one impulse. The voltage across capacitor 57, therefore, increases to successively higher values upon the application of successive impulses as indicated in Fig. 6. Impulse a, for example, charges capacitor 57 to a voltage e_1 , impulse b increases the voltage across the capacitor to the value e_2 . After a number of successive charging impulses have been applied the voltage across the capacitor, which is likewise impressed across gas tube 63, reaches or exceeds the breakdown voltage for the tube 63, and a large current flows through the tube and resistor 65, discharging the capacitor and producing an output impulse as indicated in Fig. 7.

In case the ultimate voltage across capacitor 57 is less or greater than the breakdown voltage of the gas tube 63, the operating point, that is the frequency division, may be suitably established by including a small biasing battery 67 in series with the control circuit of the gas tube. The polarity of this bias battery will be determined by the voltage ultimately built up across the capacitor and the normal breakdown voltage of the tube. On the other hand the operation may be adjusted by varying the time constant of the charging circuit.

Fig. 3 is the circuit of an embodiment of this invention combining the impulse producing arrangement of Fig. 1 with the frequency divider of Fig. 2. Since similar reference numerals refer to similar parts it will not be necessary to explain the operation of this modification.

While I have described this invention in particular application, numerous other modifica-

tions will become apparent to those skilled in the art.

For example, the thermionic tubes illustrated in Figs. 1 to 3 may be included within a single envelope, or may be replaced by grid-controlled gas tubes which are well known in the art. Likewise, the gas tube 63 illustrated in Fig. 3 may be a grid-controlled tube if desired. In case it is desired to provide current pulses rather than voltage pulses, the output resistors may be replaced by a load device through which the current will flow to discharge the capacitor.

I claim as my invention:

1. A wave converter comprising an input circuit for connection to an alternating wave source, a capacitor, means coupled to said input circuit for applying a unidirectional charging current of constant amplitude to said capacitor once for each cycle of said alternating wave, means also coupled to said input circuit and controlled by said alternating wave for discharging said capacitor through an impedance once for each cycle of said alternating wave, a rectifier, a resistor and a second capacitor serially connected across said impedance for applying a unipotential charging impulse to said second capacitor for each cycle

5 of said alternating wave, the voltage across said second capacitor being increased by each successive impulse, and means for discharging said second capacitor, said means being operated only after said voltage has reached a predetermined amplitude.

10 2. A wave converter comprising an input circuit for connection to a source of alternating voltage, a capacitor, means coupled to said input circuit for applying a unidirectional charging current of constant amplitude to said capacitor once for each cycle of said alternating voltage, means also coupled to said input circuit and controlled by said alternating voltage for discharging said capacitor through an impedance once for each cycle of said alternating voltage, a unidirectional conductor and a second capacitor serially connected across said impedance for applying a unipotential charging impulse to said second capacitor for each cycle of said alternating voltage, and means for discharging said second capacitor after a predetermined number of charging impulses have been applied to said second capacitor:
